(57) **CLAIM**

The ornamental design of a curvy key tag rack, as shown and described.

DESCRIPTION

FIG. 1 is a front elevational view of a seven key holder curvy key tag rack showing my new design;

FIG. 2 is a rear elevational view of the curvy key tag rack shown in FIG. 1;

FIG. 3 is a top plan view of the curvy key tag rack shown in FIG. 1;

FIG. 4 is a bottom plan view of the curvy key tag rack shown in FIG. 1;

FIG. 5 is a left side elevational view of the curvy key tag rack shown in FIG. 1 with the right side view being a mirror image thereof;

FIG. 6 is a perspective view of the curvy key tag rack shown in FIG. 1;

FIG. 7 is a front elevational view of another embodiment of my curvy key tag rack design showing it hold five keys instead of the seven keys shown in FIG. 1;

FIG. 8 is a rear elevational view of the curvy key tag rack shown in FIG. 7;

FIG. 9 is a top plan view of the curvy key tag rack shown in FIG. 7;

FIG. 10 is a bottom plan view of the curvy key tag rack shown in FIG. 7;

FIG. 11 is a left side elevational view of the curvy key tag rack shown in FIG. 7 with the right side view being a mirror image thereof; and,

FIG. 12 is a perspective view of the curvy key tag rack shown in FIG. 7.
